Primary Examiner — Aula Soroush(57) **CLAIM**

I claim the ornamental design for a manual breast pump, as shown.

DESCRIPTION

FIG. 1 is an isometric view of a manual breast pump in accordance with our new design;

FIG. 2 is a front view thereof;

FIG. 3 is a back view thereof;

FIG. 4 is a side view thereof;

FIG. 5 is a side view thereof, for the side opposite that of FIG. 4;

FIG. 6 is a top elevation view thereof; and,

FIG. 7 is a bottom elevation view thereof.

1 Claim, 4 Drawing Sheets(56)
